UNITED STATES PATENT OFFICE

2,060,424

METHOD OF PUTTING TOGETHER A
SHIP'S MODEL HULL

Frederick W. Megow, Philadelphia, Pa.

Application May 1, 1935, Serial No. 19,790

2 Claims. (Cl. 35—8)

This invention relates to an improved method of putting together a ship's model hull, and the purpose of the invention is to provide a method of this kind, in which the hull is made up from a plurality of pieces of wood, preferably balsa wood, which first consists of permanently cementing a previously printed sheet of wood veneer constituting a deck piece upon a block of the same material, which has been pre-shaped in the form 10 of a roughly made flat bottom canoe, then cutting said block along the printed outline on the sheet of veneer to shape the hull of the ship, then cutting out the other parts previously designated and cementing them on the hull to simulate a completed ship, said deck piece being printed with lines to simulate the boards of a deck surface.

The deck piece as previously stated, formed of soft wood preferably balsa wood is previously printed to show the various hatchways and seats 20 as well as printed for the simulation of the deck boards.

There is also provided a deck piece printed to show parts in simulation of elements to build up hatchways, seats, and other deck elements, 25 and keel, together with indications showing where masts and the like are to be placed, the deck piece being of sufficient size to furnish all of these parts as well as the deck proper.

There is further provided a ship's model hull, 30 which may have the appearance of a sea-going schooner, yacht or other vessel. This by reason of the fact that in every instance the hull comprises a hull block and a deck piece, from the latter of which the various deck elements may be 35 constructed. Certain of the hull elements are common in all of the ship's models, namely the hull block and the printed deck piece.

While Figure 1 illustrates a two masted schooner, it is obvious that a ship's model may be constructed having any number of masts.

It is to be understood that the particulars herein given of the method claimed are in no way 45 limitative, and that while still keeping within the scope of the claims, any desired modification of details and proportions may be made in the construction of the appliance according to circumstances.

The invention comprises further features and combination of parts to be hereinafter set forth, 50 shown in the drawing and claimed.

In the drawing:—

Figure 1 is a view in side elevation showing a schooner yacht.

Figure 2 is an enlarged perspective view in 55 side elevation of the ship's hull block showing a

deck piece cemented or otherwise adhesively fastened to the upper surface of the block.

Figure 3 is a plan view of the hull with the deck piece fastened thereon and having printed on its surface the simulations of various deck elements, such as hatchways, seats and holes for the reception of masts, as well as suitable illustrations of various deck elements mounted on the deck piece.

Figure 4 is a plan view of the deck piece from 10 which the hull and the various deck elements and keel may be cut.

Referring to the drawing 1 identifies a hull block which may be any size and of any shape, preferably as shown in Figure 4. A deck piece 15 2 is cemented at 3 to the upper curved surface of the block, while the opposite ends of the block have bevels 4.

On the upper face of the deck piece there is 20 printed at 6 the shape of the hull, the surface 20 of the deck piece being likewise printed to indicate the deck boards 7. There is printed on the deck piece a place for the location of a hatchway 8, as well as printed parts 10 and 11 25 for building up the hatchway. In addition to the hatchway 8 another hatchway 12 is also printed on the deck piece as well as the elements 13 to build up the hatchway 12.

A hatchway 14 including a skylight 15 is also 30 printed on the deck piece.

A hatchway indication 16 is provided, including a hatchway cover 17 with printed steps 18 leading below the cover 17.

The rear portion of the deck piece and a portion of the deck block are gouged out at 20, indicated by printing having a marginal seat 21. An upright 23 is provided and which is in such 35 position as to permit the occupancy of a pilot in front of the ship's pilot wheel 24.

Also printed on the upper face of the deck 40 piece is the outline of a keel 25, which is also cut out of the deck piece, is fastened in the proper position on the under surface of the hull, it being provided with a printed outline of a propeller 26. There may be any number of holes 27 as 45 indicated for the reception of any number of masts.

In constructing a schooner yacht of this character the deck piece after being cemented or otherwise fastened to the hull block, is shaped 50 according to the printed shape of the hull by any suitable tool or implement, and at the time that the deck piece is so shaped, the hull is likewise shaped as shown in Figure 3, and subsequently the various deck elements are cut out, shaped 55

according to their printed outline, and cemented in place on the deck piece.

The invention having been set forth, what is claimed is:

- 5 1. In an educational device, the method of constructing a model ship from a plurality of pieces of wood first by permanently cementing a previously printed sheet of wood veneer constituting a deck piece upon a block of the same
- 10 10 material which has been pre-shaped in the form of a roughly made flat bottom canoe, then cutting said block along the printed outline on the sheet of veneer to shape the hull of the ship, then gouging through said veneer and into said
- 15 15 block to form a hollow, and a seat about substantially the entire margin of said hollow, then

cutting out the other parts previously designated and cementing them on the hull to simulate a completed ship.

2. In an educational device, the method of constructing a model ship from a plurality of pieces 5 of wood first by permanently cementing a previously printed sheet of wood veneer constituting a deck piece upon a block of the wood material which has been shaped in the form of a roughly made flat bottom canoe, then cutting 10 said block along the printed outline on the sheet of veneer to shape the hull of the ship, then cutting out the other parts previously designated and cementing them on the hull to simulate a 15 completed ship.

FREDERICK W. MEGOW.
